His Attorney.

UNITED STATES PATENT OFFICE.

EDMUND G. GEORGE, OF SPRINGFIELD, ILLINOIS, ASSIGNOR OF ONE-HALF TO LESLIE HALL SIMPSON, OF GLENARM, ILLINOIS.

BOTTLE-HOLDER.

1,217,087.

Specification of Letters Patent. Patented Feb. 20, 1917.

Application filed October 15, 1915. Serial No. 56,028.

To all whom it may concern:

Be it known that I, EDMUND G. GEORGE, a citizen of the United States, and residing at Springfield, in the county of Sangamon, 5 State of Illinois, have invented a certain new and useful Improvement in Bottle-Holders, of which the following is a specification.

Milk bottles or jars of a standardized type 10 are almost universally used by dairies in the distribution of milk among their customers, and as such goods are usually distributed during early morning hours, it is the present prevailing practice, in order to save time 15 and avoid disturbing the customers, for the delivery man to simply leave the milk bottles at the doors of the houses, to be taken up later by the customers. Under this practice the goods remain for a greater or lesser 20 time, unprotected and exposed to thievery, it being known that there exists in many cities, a class of persons known as milk thieves who make a business of stealing milk after it has been thus distributed.

25 This invention relates to bottle holders of a type adapted for attachment to a door or window frame to receive and hold such bottled goods.

The invention has among its objects to 30 provide a comparatively simple, inexpensive device of this character which may be readily installed for use and which will securely retain, pending its authorized removal, a bottle placed therein.

35 Further objects of the invention are to provide a holder with which a bottle may be instantaneously engaged and one wherein the act of inserting the bottle, serves to automatically lock the latter in place.

40 A further object is to provide a bottle holder which is readily adaptable for use with either a right or left hand door, or with a window.

45 With these and other objects in view, the invention comprises the novel features of construction and combination of parts more fully hereinafter described.

In the accompanying drawings,

50 Figure 1 is a perspective view of a bottle holder embodying the invention, showing the same applied for use;

Fig. 2 is a horizontal sectional plan, the section being taken on the line 2—2 of Fig. 1;

Fig. 3 is a view similar to Fig. 2, showing the parts of the device in bottle releasing position; and

Fig. 4 is a vertical section taken on the line 4—4 of Fig. 2.

Referring to the drawings, it will be seen that the device is shown as applied to the 60 frame or casing 1 of a door 2, it being understood that these parts, which are conventionally illustrated, may be of ordinary construction and material and that the device 65 may, with equal facility, be installed for use upon a window frame, for holding a bottle 3 of the usual type having upon its neck a shoulder or bead 4.

The holder forming the subject matter of the invention embodies an upper frame plate 70 5 provided with an upturned end flange 6, suitably apertured to accommodate screws 7 by means of which the device may be securely attached to the frame or casing 1, the plate 5 being also provided with downturned 75 side flanges 8, each of which is provided at a point adjacent its rear end, with a slot or aperture 9, for a purpose which will later appear.

Disposed beneath and in spaced relation to 80 the plate 5, to provide a chamber or recess 10, is a lower frame plate 11 provided with an outwardly opening bottle receiving slot or recess 12 and having downturned side flanges 13 riveted or otherwise attached to 85 the flanges 8, there being mounted upon the plate 11, at the rear of the chamber 10, a latching bolt 14 pivoted at one end to the frame plate by means of a removable pintle 15 which may be engaged with an opening 90 16 provided at the other end of the bolt, thus adapting the device for attachment to the casing 1 at either side of the door, as will more fully hereinafter appear. The latching bolt 14, which has terminal finger 95 pieces 17 exposed respectively through the slots 9, is provided at its forward edge with an upstanding engaging portion or flange 18 and at its rear edge with an oppositely disposed finger 19 to which is attached one end 100 of an actuating spring 20 having its other end suitably engaged with the frame plate 11, through a slot 21 formed in the bolt, said spring tending to normally throw the bolt forward to engaging position.

105 Pivoted, respectively, at 22, to the plate

11 is a pair of coöperating clamping jaws 23, provided at their inner or rear ends with upturned flanges 24, whose opposed ends are spaced relatively to provide a space or recess adapting the portion 18 of the bolt to seat between said flanges, which thus form stops, and lock the jaws in clamping position, the inner active edges of the jaws being oppositely curved, as at 25, to conjointly embrace the neck of the bottle 3, below the shoulder 4, and retain the bottle within the holder. The jaws 23 are provided with terminal portions 26 at the inner ends of their active faces 25.

15 In practice the holder is attached to the frame or casing 1 at the hinged side of the door with one of the side flanges 8 lying close to the outer face of the door, whereby the latter when closed covers the adjacent slot 9, it being noted, upon reference to the drawings, that when the holder is thus attached, the latching bolt 14 will be pivoted at that end farthest removed from the door and with the finger piece 17, at its free or movable end, adjacent to the slot 9 which is thus covered. By changing the pivoting bolt 15 to engage the opening 16 at the other end of the latching bolt, the holder is adapted for attachment to the casing 1 at the other edge of the door, and the device is thus made readily adaptable for either right or left hand doors, as will be readily understood. When thus attached for use and prior to closing the door 2, the holder mechanism is set to receive a bottle by engaging the finger piece 17 and throwing the bolt 14 rearwardly against the action of spring 20, thus moving the part 18 from between the rear ends of the jaws 23, and adapting the latter to be moved to open position, as in Fig. 3, after which the door 2 may be closed and locked. It now follows that the delivery man in making his rounds, simply introduces the neck of the bottle into the slot 12 and pushes it home, whereupon the bottle through contact with the terminal portions 26, swings the jaws 23 on their pivots to engaging position, as in Fig. 2, and the spring 20 automatically throws the bolt 14 forwardly for its part 18 to seat between the stop flanges 24 and lock the jaws in bottle retaining position. These flanges also serve to close the chamber 10 in advance of the bolt 14 and prevent operation of said bolt by an instrument inserted from the front. When thus inserted the mouth of the bottle is received within the chamber 10, between the plates 5 and 11, and with the bead or shoulder 4 disposed above the retaining jaws 23, thus effectually preventing removal of the bottle or gaining access to the contents thereof, while the door 2 by covering the slot 9 prevents manipulation of the latching bolt 14 and, therefore, fraudulent removal of the bottle from the holder. To

remove the bottle the door 2 must be unlocked and swung open and the bottle is thus securely retained pending its authorized removal.

From the foregoing it is apparent that the invention accomplishes its stated objects in that the bottle may be instantaneously engaged with the holder and automatically locked in place therein pending its authorized removal. In attaining these ends, it is to be understood that the invention is not necessarily restricted to the structural details herein disclosed, as various minor changes may be made therein without departing from the spirit or scope of the invention. It is to be further understood that the term "door" wherever employed is to be read and construed to cover a window as the device may obviously be attached for use upon a window casing.

Having thus described the invention, what is claimed is:

1. A bottle holder having a chamber and adapted for attachment to the casing at either side of a door, said holder comprising a pair of coöperating bottle engaging jaws movable automatically to engaging position when a bottle is placed in the holder, a reversible latching bolt housed within the chamber and automatically operable for locking said jaws in bottle engaging position, and means constructed and arranged whereby the door, when closed, renders said latching bolt inaccessible for operation to release the jaws.

2. A bottle holder adapted for attachment to a door casing and comprising a pair of movable bottle engaging jaws mounted for free unrestricted relative movement and having inner terminal portions disposed to be struck by the bottle for moving the jaws freely into engagement with a bottle when placed in the holder, means for automatically locking said jaws in bottle engaging position, and means whereby the door, when closed, renders said locking means inaccessible for operation to release the jaws.

3. A bottle holder comprising a frame, a pair of coöperating bottle engaging jaws, a pivoted locking bolt adapted for engaging said jaws to lock them in bottle holding position, and means for pivoting said bolt at either end adapting the holder for attachment to the casing at either side of a door.

4. A bottle holder comprising a frame, a pair of coöperating bottle engaging jaws, a pivoted locking bolt adapted for engaging said jaws to lock them in bottle holding position, the ends of said bolt being accessible for operation respectively at opposite sides of said frame, and means for pivoting said bolt at either end adapting the holder for attachment to the casing at either side of a door.

5. A bottle holder comprising a frame, a

- pair of coöperating bottle engaging jaws, a pivoted locking bolt adapted for engaging said jaws to lock them in bottle holding position, and a single pivoting bolt adapted 5 to engage one end or the other of the locking bolt for reversibly pivoting the same and adapting the free end of the locking bolt for manipulation in operating said bolt to release the jaws.
- 10 6. A bottle holder comprising a frame, a pair of coöperating bottle engaging jaws, a pivoted locking bolt adapted for engaging said jaws to lock them in bottle holding position, a spring tending to move said bolt 15 to jaw locking position, and means for pivoting said bolt at one end or the other to reverse the holder without altering the position of the locking bolt or its actuating spring.
- 20 7. A bottle holder comprising a frame having a chamber, a pair of coöperating bottle engaging jaws, a locking bolt located in rear of said jaws within said chamber, said bolt being adapted for locking the jaws in bottle holding position and for movement 25 by hand to release the jaws, and means on said jaws constructed and arranged to close said chamber in front of said bolt for preventing fraudulent operation of said bolt 30 from the front.
8. A bottle holder comprising a frame having a chamber, a pair of coöperating bottle engaging jaws, a locking bolt located in rear of said jaws within said chamber, said bolt being adapted for locking the jaws 35 in bottle holding position and for movement by hand to release the jaws, and flanges on said jaws constructed and arranged to close said chamber in front of said bolt for preventing fraudulent operation of said bolt 40 from the front.

In testimony whereof I affix my signature
this 20th day of September, 1915.

EDMUND G. GEORGE.
